UNITED STATES PATENT OFFICE

JOHANES A. F. OSSE, OF SHELDON, IOWA

DEVICE FOR SPREADING AND ENLARGING MOTOR PISTONS

Application filed August 21, 1931. Serial No. 558,604.

This invention relates to a device for spreading and enlarging motor pistons.

An object of my invention is the provision of simple and efficient means for enlarging or spreading a worn or used piston, so that its utility or efficiency will be restored completely.

Another object of the invention is the provision of means in the slot of the sleeve of a piston for spreading or enlarging a worn or used piston, whereby its original utility or efficiency is completely restored.

A still further object of the invention is the construction of a novel and efficient spreading or wedging device for use in the slot of a worn piston for causing such piston to again have one hundred per cent efficiency.

With the foregoing and other objects in view, my invention comprises certain novel constructions, combinations and arrangements of parts as will be hereinafter fully described, illustrated in the accompanying drawing, and more particularly pointed out in the appended claims.

In the drawing:

Figure 1 is a view in side elevation of a piston showing my invention applied thereto.

Figure 2 is a view in side elevation of a piston, having my peculiar slot structure, and the spreading or wedging device removed.

Figure 3 is a sectional view taken on line 3—3, Figure 1 and looking in the direction of the arrows.

Figure 4 is a sectional view taken on line 4—4, Figure 1, and looking in the direction of the arrows.

Figure 5 is a sectional view taken on line 5—5, Figure 1, and looking in the direction of the arrows.

Figure 6 is a perspective view of the spreading and enlarging device.

Referring to the drawing by numerals, 1 designates the piston as a whole, which includes the ordinary sleeve 2. In the following claims, I refer to a piston with a slot, meaning the sleeve 2 with its longitudinally extending slot 3.

The slot 3 has an enlarged portion 4 formed by preferably semi-circular notches 5, 5. The slot 3 contiguous to notches 5, 5 (Fig. 2) is slightly bevelled on its outer edge, as at 6, for the purpose hereinafter specified.

A spreading and enlarging device 7 (Fig. 6) is provided comprising elongated body 8, which has at its center preferably a cylindrical enlargement 9. This enlarged portion 9 is provided with an aperture 10. The elongated body is provided on its inner edge with oppositely extending flanges 11, 11.

It is to be understood that when the face of the piston wears, it becomes too small for the cylinder. Heretofore such a situation has required the use of a new piston. By using my invention, the old piston can be used again with the same efficiency as an entirely new piston.

The aperture 10 in the device 7 is to permit the insertion of a punch. The device is inserted into the slot 3 from the bottom or inside of the piston with the flanges 11 touching the inner part of the piston, while the enlarged central portion 9 fits the semi-circular notches 5, 5 of slot 3. The device 7 is then held in place from the bottom while the operator hammers a punch in the aperture 10 causing the enlarged or rounded part 9 to spread out against the notches 5. The device 7 is of such size that approximately one eighth of an inch protrudes above the outer surface of the piston. After the center of device 7 has been pounded and spread into place with a hammer and punch, the balance of the device is then pounded down so that the entire surface is even with the outer surface of the piston (see Fig. 5) and being thereby firmly fitted into the slot of the sleeve 2. This hammering of the device 7 causes part to be forced against the bevelled edges 6, 6 (Figs. 2 and 5), whereby the device is securely locked in place. The enlarged portion 4 of slot 3 and the enlarged portion 9 of device 7 efficiently prevents any creeping or longitudinal movement of the wedging device when in position. As a rule, the wear on an old piston reduces its outer dimension by only a small fraction of an inch, and by the use of my invention, the piston can be 100

95
100

spread and enlarged to the size desired, so that it will fit the cylinder like a new piston. Obviously, the device 7 can be of any size required. Its texture should be substantially

6 the same as that of the piston itself.

While I have described the preferred embodiment of my invention and illustrated the same in the accompanying drawing, certain minor changes or alterations may appear to one skilled in the art to which this invention relates, during the extensive manufacture of the same, and I, therefore, reserve the right to make such changes or alterations as shall fairly fall within the scope of the

15 appended claims.

What I claim is:

1. A device of the class described, comprising an elongated substantially rectangular body provided at its center with a substantially cylinder-like portion hollow at its center, and said body provided with outwardly extending flanges its full length and at the same side edges, substantially as shown and described.

2. A single-piece spreading device, comprising a body, said body provided with a punch-receiving aperture at an angle to the longitudinal axis of said body, and said body provided with integral flanges its entire length and extending therefrom in opposite directions.

3. A single-piece spreading device, comprising an elongated body, said body provided at its center only with an aperture formed at right angles to the longitudinal axis of said body, said body provided with integral flanges its entire length, and said flanges projecting in opposite directions from the same edge of said body.

4. A single-piece spreading device, comprising an oblong body provided with outwardly extending flanges along one edge, and with a transverse punch-receiving aperture between its ends.

45 In testimony whereof I hereunto affix my signature.

JOHANES A. F. OSSE.
